UNITED STATES PATENT OFFICE.

WILLIAM B. WALLACE, OF BELLEVILLE, ILLINOIS.

STEAM-BRAKE FOR LOCOMOTIVES.

SPECIFICATION forming part of Letters Patent No. 278,299, dated May 22, 1883.

Application filed November 16, 1882. (No model.)

To all whom it may concern:

Be it known that I, WILLIAM BALFOUR WALLACE, a citizen of the United States, residing at Belleville, in the county of St. Clair and State of Illinois, have invented certain new and useful Improvements in Steam-Brakes for Locomotives, of which the following is a full, clear, and exact description, reference being had to the accompanying drawings and letters of reference marked thereon, in which—

Figure 1 is a top view of my improved steam-brake as in a state of rest, with the upper plate, A, removed. Fig. 2 shows the same parts as in the act of operating the brake-lever Z. Fig. 3 is a perspective view of the steam-receptacle, in which is placed the valve for operating the brake. Figs. 4, 5, 6, 7, 8, 9, and 10 are detail views of my invention.

Similar letters indicate like parts in all the figures.

My invention relates to improvements in steam-brakes for locomotives; and it consists in the peculiar construction and arrangement of the parts, as hereinafter more fully set forth, and pointed out in the claims.

In the accompanying drawings, C represents a steam-cylinder, open at one end and closed at the opposite end, and provided with a piston, P, and a steam-port, x, near its closed end.

A A' represent two parallel right-angular plates, of the same dimensions, connected together at their outer corners by the rollers c c, journaled in the plates A A', which are open at their inner ends to receive the cylinder C.

Between the plates A A', near their inner ends, and on opposite sides of the cylinder, are the opposite curved levers D D, having for their fulcra the pins b b, journaled in the plates A A'. The curved levers D D are provided with rollers d d at their ends.

g g represent inclined planes, with their larger ends toward the open end of the cylinder C, and their bases abutting or lying in contact with the sides of the cylinder.

E E represent arms lying on opposite sides of the cylinder, near its closed end, in the same right line at right angles to the axis of the cylinder.

The piston P projects beyond the open end of the cylinder C, into the space between the

plates A A', to which it is secured. The cylinder C, with its piston P, the plates A A', carrying the curved levers D D, the arms E E, and the inclined planes g g are secured in any convenient manner below the floor of the engineer's cab. One of the arms, E, is provided with a lug or projection, a, to which is secured one end of a chain, N, which passes thence partly around the rollers d of one of the levers D; thence around the rollers c c, and partly around the rollers of the opposite lever D; thence partly around the roller a' on the opposite arm E, the opposite end of the chain being pivotally secured to one end of the rod O, the opposite end of said rod O being pivotally connected with the brake-lever Z, fulcrumed at h and carrying a brake bar or shoe at its lower end.

It will be seen in this construction that the inner rollers of the levers bear on the inclined planes g at their inner or smaller ends, and that the chain N is straight on the opposite sides of the loop formed in it.

Y represents a closed cylindrical steam-receptacle securely fastened in some convenient place, preferably above the engineer's head, and provided at its upper end with a pipe, K, leading to the steam-space of the boiler of the locomotive.

r' is a port in the lower part of the steam-receptacle Y, and R is a pipe connecting the port r' in the steam-receptacle with the port x in the inner end of the cylinder C, whereby steam is admitted into the latter to drive the piston P.

p p and e are ports in the steam-receptacle Y, the former ports, p p, leading into the exhaust-pipe m, and the latter port, e, leading into the shorter pipe n, lying within and surrounded by the exhaust-pipe m.

V represents a curved valve adapted to fit in the lower part of the steam-receptacle Y. The front face of the valve V is provided with the parallel studs T T, with a space, w, between them, adapted to receive the arm S of the lever L, which arm S extends from a disk, s, to which the lever L is fastened, the valve V being rocked to and fro in the steam-receptacle Y by oscillating the lever L at right angles to its arm S. The valve V is provided with

the ports $p' p'$, adapted in one position of said valve to register with the ports $p p$, leading to the exhaust-pipe m , and the back face of the valve V is provided with a recess, r , which in 5 one position of the valve V connects the port r' of the pipe R with the port e of the pipe n .

q represents a quadrant, arranged concentrically below the cylindrical steam-receptacle Y . The quadrant q is provided with the recesses $o o' o''$ to receive and hold the lever L and valve V when oscillated. When the lever is in the recess o the piston P is in the position shown in Fig. 1, all the ports are closed, the brake is not applied, the opposite sides of 15 the loop in the chain are straight, and the parts are in their normal condition.

If it is desired to apply the brake, the lever L is oscillated and made to engage with the recess o'' , which brings the valve into the position shown in Fig. 10, and opening the port r' , whence the steam escapes through the pipe R into the cylinder through its port x and forces 20 the piston outward, and with it the plates $A A'$, to which the lower end of the piston is secured. In the outward movement of the plates $A A'$ the inner rolls, $d d$, of the levers $D D$, riding on the inclined planes, will assume the 25 position shown in Fig. 2, and the opposite sides of the loop in the chain will assume a bent or zigzag form and move the brake-lever arm Z more than twice as far as the piston is moved, or the brake-lever arm Z will be moved as 30 much farther as the difference between a straight line and the length of these zigzags or bends in the chain.

If it is desired to stop the action of the brake, the lever L is moved to the recess o' of the quadrant q , as shown in Fig. 9. This movement brings the recess r in the back face of 35 the valve V over the port r' of the pipe R and over the port e of the short pipe n , and also connects the ports $p' p'$ of the valve with the ports $p p$ of the exhaust-pipe m , thus permitting the steam to escape from the receptacle Y . The steam escaping through the pipe m , which surrounds the pipe n , causes the air in the pipe n to be rarefied, or a partial vacuum will be formed therein, and the steam in the cylinder C will pass through the pipe R , thence 45 through the recess r in the valve V to the port

e , and thence to the pipe n , and thence to the pipe m , leaving no steam in the cylinder C and a partial vacuum in its steam-space, when the outward pressure of the air will force the piston back into the cylinder, and with it the frame $A A'$, leaving the opposite sides of the 55 loop in the chain straight.

What I claim as my invention, and desire to secure by Letters Patent, is—

1. The combination, with the arms $E E$ and 60 the cylinder C , provided with the piston P , of the plates $A A'$, secured to the piston and having guide-rollers $c c$, chain N , and brake-lever Z , substantially as described.

2. The combination, with the inclined planes 65 g , arms $E E$, and cylinder C , provided with the piston P , of the plates $A A'$, secured to the piston, and provided with the guide-rollers c and levers D , having rolls d at their ends, chain N , and brake-lever Z , substantially as 70 described.

3. The combination, with the plates $A A'$, secured to the piston and provided with the guide-rollers c and levers D , arms $E E$, inclined planes g , chain N , and brake-lever Z , of the 75 cylinder C , provided with the piston P and port x , steam-pipe R , and steam-receptacle Y , substantially as described.

4. The combination, with the cylinder C , provided with the piston P and steam-port x , of 80 the pipe R , steam-receptacle Y , having port r' , and rocking valve V , substantially as described.

5. The combination, with the cylinder C , provided with the piston P and port x , of the pipe 85 R , steam-receptacle Y , provided with the pipe K , ports $r' p p e$, exhaust-pipe m , pipe n , and rocking valve V , provided with the ports $p' p'$ and recess r , substantially as described.

6. The combination, with the steam-receptacle Y , provided with the pipes $K R m n$ and ports $p p e r'$, of the rocking valve V , provided with the ports $p' p'$, recess r , and studs $T T$, lever L , having arm S , and quadrant q , having recesses $o o' o''$, substantially as described. 90
